DRUM HANDLING DEVICE
Robert J. Trotter, 1218 S. Midvale Blvd.,
Madison, Wis.
Filed Nov. 27, 1957, Ser. No. 699,416
6 Claims. (Cl. 214—653)

This invention pertains to a device for carrying and dispensing liquids from a drum.

The device is further characterized by providing a pumping apparatus integral with a drum carrying device.

One of the great disadvantages in certain previous devices has been that much time has been spent and liquid lost in transferring a liquid from a container in which it is received to a reservoir in a liquid dispensing device which may be used to deliver the liquid to its point of ultimate use.

A great disadvantage of those devices used to pick up a drum carrying a liquid, has been the difficulty encountered in so doing wherein the operator must force a lifting member under the drum and must cause a plurality of arms to grasp the drum prior to picking up same. Also, in most such devices the drum is not securely and positively held in place and with relative ease it may be accidentally dropped from the device with consequent great possibility of serious injury to personnel in the area.

It is therefore an object of this invention to provide a device wherein a drum of liquid is picked up and carried in the device.

Another object is to provide a gripping device and lifting mechanism, integral with the device, that enables an operator to quickly and easily pick up a drum of liquid.

Another object is to provide a device wherein the actual container holding the liquid is utilized as the reservoir of the device.

Still another object is to provide a pump integral with the device, wherein the receiving base of the pump is easily attached in an operable fashion to the "carried" drum.

Other objects will become apparent from the drawings and from the following detailed description in which it is intended to illustrate the applicability of the invention without thereby limiting it to a scope less than that of all equivalents which will be apparent to one skilled in the art. In the drawings, like reference numerals refer to like parts and in which:

FIGURE 1 is a perspective view of a drum handling device according to the invention;

FIGURE 2 is a perspective view of a drum handling device carrying a drum of liquid, and taken from the opposite side of the device as that view in FIGURE 1;

FIGURE 3 is a cross-sectional elevation of the gripping mechanism of the device in the closed or gripping position;

FIGURE 4 is a cross-sectional elevation of the gripping mechanism of the device in the semi-open position;

FIGURE 5 is a cross-sectional elevation of the gripping mechanism of the device in the open position.

Referring now to the drawings and more particularly to FIGURES 1 and 2, wherein 1' is a bifurcated horizontal frame having a lower cross-wise support member 2 attached thereto, as by welding or any similar means at the base of frame 1' and a second support member 3 attached thereto in the same manner as support 2 at the upper side of frame 1'. On either side of the frame 1' at that extremity of same most remote from support members 2 and 3 there are located two wheels 12 and 12' which, in conjunction with caster wheels 11 and 11' (mounted on frame 1' substantially toward the rear of the frame beneath the support members 2 and 3) serve to provide mobility to the device. Bifurcated frame 1'

2

is also characterized by having barrel positioning lugs 13 on the inside of either side of same. (One lug not shown for the sake of convenience.)

Extending vertically upward from support member 3 and attached thereto are two additional frame members 1 and 1" which are additionally attached to the bifurcated frame member 1' by supports 4 and 5. Mounted on one of the vertical frame members is a suction pump 6 having an operating handle 7 and receiving and dispensing hoses 8 and 9 respectively. Note that pump 6 is in no way attached to frame member 23. On the inner sides of frame members 1 and 1" are a plurality of bearing members 17 which are adapted to receive the legs 16 of an inverted adjustable U-shaped frame 23. Bearing members 17 are preferably sheaves rotatably mounted on pins 17' which are securely attached to members 1 and 1" as by welding. Attached to the upper portion 10 of the inverted U-shaped frame is a hydraulic jack 14 comprising a stationary piston 19 attached to cross support 3, 20 and a movable cylinder 18 and an operating handle 29 to operate hydraulic pump 29'. Extending at right angles from portion 10 of U-shaped frame 23 and extending toward the open portion of frame 1' is gripping housing mechanism 24. It can thusly be seen that when jack 25 handle 29 is operated to operate pump 29', inverted U-shaped frame 23 moves upward in frame 1 and 1" carrying with it the cylinder 18 of jack 14 and gripping housing mechanism 24; downward movement of said members results from the force of gravity acting thereon when bypass valve 29" is opened.

Referring now to FIGURE 2, a drum 15 is shown in the device juxtaposed to bifurcated portion 1' and gripped by the gripping mechanism which is shown in the closed position.

35 FIGURE 2 also discloses the pusher bar 25 which is firmly attached to the legs 16 of inverted U-shaped member 23.

Referring more particularly now to the gripping mechanism of FIGURE 3, normally stationary jaw 20 is adjustable to an extent as by the action of bolt 26 (FIGURE 1), which is threadably received in a stationary block 27 and wherein said bolt is adapted to act on jaw 20 which is slidably received in ways 20" to bias jaw 20 along portion of the extent of gripping housing mechanism 24.

45 This adjustable feature of jaw 20 is designed to compensate for wear on the jaw or for different size barrel rims.

A second jaw 20' adapted to be opposite, when in the closed position, to jaw 20 and adapted in conjunction with jaw 20 to fixably grasp a barrel rim therebetween, is positioned at the lower end of a pivoted member 30, which at its upper extremity is pivotally connected to a second member 22 which is part of handle 21 and located at substantially right angles thereto. A third member 31 is pivotally connected to member 22 and pivots around a fixed pivot 32.

In operation, in order to disengage jaws 20' and 20, handle 21 (FIGURE 4) is moved counter-clockwise thereby causing member 22 to move in a counter-clockwise direction which in turn causes member 30 to pivot in a clockwise direction around pivot 35 and member 31 in a clockwise direction around pivot 32. As the handle 21 is moved further in a counter-clockwise direction, (FIGURE 5) member 30 continues to pivot in a clockwise direction around pivot 35, but member 31 changes its direction and continues in a counter-clockwise direction for a distance.

It is to be noted that in the reverse sequence of operation, a stop 36 is provided (FIGURE 3) to keep member 31 from continuing in clockwise direction, which, if allowed to occur, would destroy the locking effect of the jaws.

In practice then, when for example quantities of oil or gasoline or like liquid materials are needed in a plant or factory in differing amounts, the drum handling device is wheeled up to a drum containing the necessary material and the bifurcated horizontal frame 1' is made to juxtapose the base of the drum, aided by the positioning members 13 and 13'. Next the vertical adjustable inverted U frame 23 is adjusted to a height sufficient to enable the gripping jaws 20 and 20' to be positioned on either side of the upper lip of the drum 15. The handle 21 of the gripping mechanism is activated and the gripping jaws are caused to firmly grasp, in a locked relation, the lip of the drum.

As a final step, the drum is raised a slight vertical distance by cranking the handle 29 of the hydraulic jack, and the receiving hose 8 is inserted in the drum through a hole in the top of same. Then whenever the gasoline, lubricant, etc. in the drum is needed, anywhere throughout a manufacturing plant, the device is pushed by an operator, grasping pushing bar 25, to that location and the liquid is dispensed by turning the handle 7 of the pump 6.

In unloading the device, hose 8 is removed from the drum, frame 23 is lowered, the gripping mechanism is opened and the device backed away from the drum.

It can be seen that a device of this kind has many inherent advantages, among them:

- (1) Efficient use of man hours.
- (2) Speed in delivery of the liquid material to the required destination.
- (3) Minimization of manual lifting, etc.
- (4) High degree of mobility of the device.

While in the preferred modification of this device a suction pump is incorporated, it is entirely possible to incorporate a suction pump in reverse, or a combination of the two thereby enabling the device to pick up, as for disposal, quantities of liquid material as well as to dispense liquid.

While certain modifications and embodiments of the invention have been described, it is of course to be understood that there are a great number of variations which will suggest themselves to anyone familiar with the subject matter thereof, and it is distinctly understood that this invention should not be limited except by such limitations as are clearly imposed in the appended claims.

Having thus disclosed my invention, I claim:

1. A wheeled vehicle comprising a bifurcated horizontal frame adapted to support a drum; support members for said horizontal frame; vertical frame sections affixed to said horizontal frame and containing a plurality of bearing members; a vertically adjustable inverted U frame adapted to be slidably received between said bearing members on said vertical frame sections; said U frame having affixed thereto and extending outwardly therefrom a member supporting a gripping mechanism; said gripping mechanism comprising a plurality of jaws, one of which is stationary with respect to the upper rim of said drum, the other of which is pivoted to the gripping support mechanism and moveable with respect to said upper rim of said drum; said gripping mechanism further characterized by being adapted to retain said drum upper rim by said moveable jaw being clamped onto said rim by actuation of a toggle joint to which said moveable jaw is pivotally affixed and which is pivotally affixed to said member; a hydraulic jack affixed at its upper extremity to a portion of said inverted U frame and affixed at its lower extremity to one of said support members for said horizontal frame and adapted to occasion the vertical movement of said inverted U frame.
2. A device as in claim 1 wherein said stationary

jaw is adjustable to a degree in a direction along the extent of said gripping support member.

3. A device as in claim 1 wherein said bearing members constitute a plurality of rollers.

- 5 4. A wheeled vehicle comprising a bifurcated horizontal frame containing positioning lugs adapted to position a drum therebetween; a plurality of wheels rotatably affixed to said frame; support members uniting both sides of said bifurcated frame; vertical frame members affixed to one of said support members and containing a plurality of bearing members affixed thereto; one of said vertical frame members further characterized by having affixed thereto a pump which is characterized by an operating handle and receiving and dispensing means; an adjustable frame member adapted to be received between said bearing members on said vertical frame; a jack member having an operating handle and having the upper extremity of said member affixed to a portion of said adjustable frame member and having its lower extremity affixed to one of said support members and adapted to occasion the vertical movement of said adjustable frame member; said adjustable frame member further characterized by having a portion extending outwardly therefrom and affixed thereto which
- 10 15 20 25 30

is adapted to house a gripping mechanism comprising a plurality of jaws, one of which is normally stationary, the other of which is pivoted around a fixed point and is pivotally connected to one link of a toggle joint, said toggle joint having an operating handle, said toggle joint being relatively affixed to said adjustable frame member.

- 35 40 45 50
5. A device for lifting and transporting a container having an upstanding rim comprising spaced apart horizontal frame members adapted to support said container, support members for said horizontal frame members, vertical frame members affixed to said horizontal frame members and carrying a plurality of bearing members, a vertically adjustable frame adapted to be slidably received by said bearing members, at least one load restraining member extending outwardly transversely from said vertically adjustable frame and provided with means for positively engaging with said load, said load restraining member configured with an abutting jaw and a biasable jaw disposed to contain therebetween a rim of a container, said biasable jaw being operably affixed to a toggle joint so as to be actuatable thereby said toggle joint being rotatively affixed to said load restraining member, jack means attached to said frames to provide for substantially vertical movement of said vertically adjustable frame.

- 55 60 65 70 75
6. A device for gripping and retaining the rim of a barrel comprising two displaceable jaws, one of said jaws being rotatively moveable, a toggle joint comprising two links, said rotatively moveable jaw being pivotally affixed to one link of said toggle joint, the other link of said toggle joint being pivotally affixed to the frame of said device, said toggle joint being operably moveable to cause said rotatable jaw to be brought into close adjacency with said slideable jaw with said barrel firmly restrained therebetween.
